UNITED STATES PATENT OFFICE

FREDERICK BINNIER AND GEORGE E. UNDERWOOD, OF ROYAL OAK, MICHIGAN

DESIGN FOR AN INCENSE BURNER

Application filed November 23, 1929. Serial No. 33,535. Term of patent 7 years.

To all whom it may concern:

Be it known that we, FREDERICK BINNIER and GEORGE E. UNDERWOOD, citizens of the United States, residing in the city of Royal Oak, county of Oakland, and State of Michigan, have invented a new, original and ornamental Design for an Incense Burner, of which the following is a specification, reference being had to the accompanying drawing, forming a part thereof.

The figure is a perspective view of an incense burner showing our new design.

We claim:—

The ornamental design for an incense burner as shown.

FREDERICK BINNIER.
GEORGE. E. UNDERWOOD.
